UNITED STATES PATENT OFFICE.

MICHAEL EWASZCZYSZYN, OF AMSTERDAM, NEW YORK.

SHOE-POLISHING DEVICE.

Application filed September 12, 1921. Serial No. 500,264.

To all whom it may concern:

Be it known that I, MICHAEL EWASZCZYSZYN, a citizen of Ukraine, residing at Amsterdam, county of Montgomery and State 5 of New York, have invented certain new and useful Improvements in Shoe-Polishing Devices, of which the following is a specification.

This invention relates to improvements in 10 shoe polishing devices, and it is the principal object of the invention to provide a simple and inexpensive device of this class which performs its function automatically upon a depression of a frame by the foot.

Another object of the invention is the provision of an apparatus of this character including a means for cleaning the soles and 15 heels of shoes or the like.

A further object of the invention is to provide an apparatus of this class which can be 20 easily moved from place to place and set up at any desired locality and which takes up a limited space only.

These and other objects will become more 25 fully apparent as the description thereof proceeds and will then be specifically pointed out in the appended claims.

In the accompanying drawings forming a part of this disclosure—

30 Figure 1 is a top plan view of a shoe polishing device constructed according to the present invention.

Figure 2 is a longitudinal vertical section through the device on line 2—2 of Figure 1.

35 Figure 3 is a similar view taken through the upper part of a frame used with the device on line 3—3 of Figure 1, and

Figure 4 is a vertical cross section on line 4—4 of Figure 1.

40 The apparatus comprises a box 10 of any desired material, the front wall of which is provided at its lower part with a door 12 covering an opening allowing access to the lower part of the box for the removal of 45 dirt or storage of polishing material etc.

To the inner faces of each of the end walls of this box are secured near their upper ends two cleats 13, each of which carries a hook or the like 14 to which is attached the upper end of a strong coiled spring 15, the lower end of which is secured to an eye 16 on the outer end face of a frame 17, so that this frame is freely suspended within the box from said springs 15 and can 55 be depressed by a foot placed upon a grating

18 within said frame against the action of said coiled springs.

The grating or metal frame 18 consists of longitudinal bars or rods 19 connected at their ends by cross rods 20.

At the front end of the box the ends of angle bars 21 are secured to the rod 20 as indicated in Figure 3 in order to provide a space for the heel, the other ends of these bars 21 are secured in the end bar 17 of the 65 frame.

Longitudinally extending brushes 22 are journaled at one of their ends in suitable bearings 23 on the top edges of the frame while their opposite ends are secured in 70 sockets 24 (Figure 4) protruding from segmental slots 25 in a metal plate 26 vertically arranged at one end of the frame 17. Another vertical plate 27 is arranged parallel to plate 26 in rear thereof.

Between the two plates toothed segments 28 are secured by pins 29 and the teeth of the segments are in mesh with the teeth of a pinion or gear wheel 30 on sockets 24. To the ends of the stems of brushes 22 engaging 80 the sockets 24, are secured the upper ends of lever 31, the lower ends of which are pivotally connected with the front plate 26 as at 32. Behind the ends of the levers 31 are secured to the brush stems the upper 85 ends of angular levers 33, the lower ends of which are pivotally secured as at 34 to pins 35 projecting from the inner faces of the side walls of the box 10.

At the bottom 36 of the box, hooks 37 are 90 provided to which the lower ends of cables 38 are secured which are guided over rollers or pulleys 39 arranged in suitable guides 40 secured to the outer face of the side bars of the frame 17, and the other ends of the cables 38 are guided upwardly and secured to eyes 40' protruding from the inner face of the end walls of the box 10. Racks 41 are fastened to the outer lateral faces of the frame 17, and gear wheels 42 are in mesh 100 with these racks and are carried at the outer ends of the stem of brush 43 arranged transversely in the frame 17 and projecting through the side bars of the frame. The stem of this brush 43 travels in a longitudinal slot 44 in the side bars of frame 17 and carries at its extreme outer end cleats 42' which are secured to the cables 38.

The stem 46 of a brush 45 is also arranged transversely in the frame 17, and projects 110

with its ends through the side bars of this frame and carries at its ends sprocket wheels 47 each in mesh with a sprocket chain 48 secured at its lower end to an eye 49 in the bottom of the box and with its upper end to a pin 50 projecting from the inner side wall of the box 17.

The device operates as follows:

A person desiring to have his shoes shined 10 or polished rests his foot with its sole on grating 18 with the heel resting on lower bars 21. If he now presses with his foot downward, the entire frame 17 will execute a downward movement against the action 15 of springs 15 the downward movement of the frame 17 will compel the gears 30 to climb the segments 29 thus rotating the brushes 22 which have previously been provided with a polishing substance, to polish 20 the point, sides and uppers of the shoe, while the cables 28 will operate brush 43 to clean the sole and the sprocket wheels 47 will engage the chains 48 and will rotate brush 45 to clean the heel.

Having thus described my invention what I claim as new and desire to secure by Letters Patent of the United States is—

1. A shoe polishing machine of the class described, comprising a box, a frame in 30 said box, springs for suspending said frame for vertical movement in said box, a pair of longitudinally arranged brushes on said frame, means for rotating said brushes upon the depression of said frame by a foot, a 35 pair of transverse brushes in said frame, and means for rotating said transverse brushes for cleaning the sole and heel of a shoe.

2. A shoe polishing machine of the class 40 described, comprising a box, four cleats projecting above the upper edge of said box each provided with a hook, a frame, springs secured to said frame and to the hooks of 45 said cleats, a grating in said frame having a somewhat lower portion at one end, two spaced, parallel, vertical plates secured at one end to said frame, one of said plates provided with a pair of segmental slots, a 50 pair of toothed segments secured between both plates, a pair of gears in mesh with the teeth of said segments, a socket on each of said gears projecting through said slots and a pair of brushes longitudinally disposed on top of said frame, and each having 55 one end of its stem journaled in one end of the frame and its other end in engagement with said socket at the opposite end of said frame, means for operating said gears to

ride on said segments for rotating said brushes upon the depression of said frame 60 by a foot, and means for cleaning the sole and heel of a boot or shoe to be polished by said brushes.

3. In a shoe polishing machine of the character described comprising a box, a 65 frame, means for suspending said frame in said box for vertical reciprocatory movement, a pair of toothed segments, spaced plates for holding said segments, gears in mesh with said segments, sockets in said 70 gears, a pair of longitudinally disposed brushes in said frame, the stems of said brushes mounted at one end for rotation on said frame and engaging with their opposite ends said sockets, a pair of levers pivotally secured at one end to one of said 75 plates and engaging with their opposite ends the stems of said brushes, and a pair of angular bars secured at one end to the inner side walls of the box and with their 80 other ends to the stems of said brushes for guiding said brushes during their rotation to polish a shoe, and adapted to guide the parts back into their normal positions after the polishing operation, and means for 85 cleaning the sole and heel of a shoe.

4. In a shoe polishing machine of the character described, comprising a box, a frame suspended in said box for vertical reciprocatory movement, a transverse brush 90 having its stem projecting through a longitudinal slot in the side bars of said frame, gears on the ends of the stem of said brush, a pair of racks secured to the outer faces of the side bars of said frame with the teeth 95 of which said gears are in mesh, a pair of cables secured with one end to the bottom of said box, pairs of pulleys secured to the side bars of said frame over which said cables are guided, and hooks at the end walls 100 of said box to which the other ends of said cables are guided, plates on the ends of the stems of said brushes laterally disposed to said gears and secured to said cables, another transverse brush having its stem journaled in the side bars of said frame, means 105 for operating said transverse brush, and a grating on said frame having a sole engaging part and a lower heel engaging part for supporting the shoe to be polished upon the 110 depression of said frame against the action of said frame suspending means.

In testimony whereof I have affixed my signature.

MICHAEL EWASZCZYSZYN.
